ELECTRIC SWITCH FOR DOOR JAMBS

Hugh W. Batcheller, Newton Highlands, Mass.

Application August 31, 1949, Serial No. 113,433

1 Claim. (Cl. 200—159)

1

This invention relates to an electric switch of the push-button type adapted to be mounted on a door jamb so as to be operated by pressure of the edge of the door as the latter is opened and closed.

One specific use of switches of this kind is on jambs of automobile doors, the purpose being to provide illumination within the automobile automatically whenever one of its doors is opened, the closing of the door resulting in the extinguishing of the light. Switches for this and similar purposes have been in use for many years. The object of the present invention is to provide a switch the parts of which are so designed as to be made and assembled easily and cheaply, the switch itself being adapted to be quickly and permanently mounted in a door jamb.

For this purpose, most of the metal parts of the switch structure are sheet metal stampings which can be readily assembled with a block, disk and ring of insulating material. The assembled parts of the switch are secured together by two simple crimping operations.

The completed switch is adapted to be mounted on a door jamb, being thrust into a preformed hole in the jamb which receives the switch housing, spring means being provided to retain the switch permanently in place. For a more complete understanding of the invention, reference may be had to the following description thereof, and to the drawing, of which

Figure 1 is an exploded view of a switch structure embodying the invention;

Figure 2 is a side elevation of the assembled switch, partly broken away to show in section;

Figure 3 is a section on the line 3—3 of Figure 2;

Figure 4 is a side elevation of the switch with the bottom pushed part way in, a portion being broken away to show in section; and

Figure 5 is a perspective view of a block of insulation which is a part of the structure shown in the other figures.

The switch illustrated in the drawing comprises a base block 10 of insulation such as a suitable molded plastic. This block is generally cylindrical in shape with two wide longitudinal ribs 12 and 14. Shortly below its top face, the block is reduced slightly in diameter to form a narrow circumferential shoulder 16 which is interrupted by the ribs 12 and 14. Two parallel longitudinal bores 18 and 20 extend through the block and are suitably spaced apart. Between these bores are a pair of rectangular holes 22 and 24 each of which extends longitudinally into the block from

the top face thereof and terminates near the bottom of the block. For convenience in describing the switch in the specification and claims, it will be thought of in a vertical position as shown in Figure 2, the base block being at the bottom and the plunger at the top. Each of the rectangular holes 22 and 24 opens laterally into one of the bores 18 and 20 so that the cross-sectional areas of a bore and its corresponding hole on a common plane are a circle and a rectangle which overlap slightly, that is, have a common area in the form of a segment of the circle. The rectangular holes 22 and 24 are parallel and between them is a tongue 26 which projects up above the top face of the block, the broad sides of the tongue being continuations of side wall faces of the two holes 22 and 24.

Overlying the block 10 is a disk or plate 30 of insulating material such as vulcanized fibre. The disk is shaped to fit upon the top of the block and upper ends of the ribs 12 and 14 and is provided with a central rectangular aperture through which extend two conductors 32 and 34 which are strips of a suitable resilient metal or alloy such as bronze. These conductors extend downward in the rectangular holes 22 and 24 respectively, and the lower ends of the conductors are at the bottoms of these holes as indicated in Figure 2. The lowermost portion of each of these conductors is reversely bent as at 36 so that a surface thereof projects slightly into the adjacent bore. Thus when a suitably shaped plug 38 on the end of a circuit wire is thrust into one of the bores 18 or 20, it engages the reversely bent lower portion of corresponding conductor and makes a good electrical contact therewith. The conductor also serves to hold the plug yieldingly in its inserted position as shown in Figure 2. In assembling the switch, the conductors 32 and 34 are first assembled with the block 10 and disk 30, the central aperture in the washer being just wide enough to receive the tongue 26 and the conductors 32 and 34. These members are thus firmly held together in an assembled relation by the disk 30. The portions of the conductors 32 and 34 which project above the disk 30 are approximately parallel except for the upper portions which are bent out as at 38 and then up as at 40 to diverge from each other.

Seated on the top of the disk 30 is the circular base 42 of a metal fastening member having upwardly projecting arms 44 and 46 to hold the assembly in its mounted position as hereinafter explained. A tubular shell 50 surrounds the conductors 32 and 34 and is secured to the block

10. The shell 50 has notches 52 and 54 extending up from its bottom edge to straddle the ribs 12 and 14. The bottom edge portions of the shell between the notches 52 and 54 are spun over the shoulders 16 of the block 10 to secure the shell to the block. The shell at its upper end is provided with an outwardly projecting flange 56 for a purpose hereinafter explained.

Within the shell 50 is a helical spring 60 which surrounds the conductors 32 and 34 but is spaced therefrom so as not to touch them. Bearing against the upper end of the spring 60 is an annular washer 62 of insulation. Mounted within this annular washer is a metal ring 64 which serves as a bridging conductor by simultaneous contact with the conductors 32 and 34. The lower portion of the metal ring 64 is flared as at 66 to facilitate assembling with other members of the switch.

20 The washer 62 bears against a shoulder 68 of a hollow cylindrical plunger 70 which is closed at the top and has a lower portion 72 of increased diameter.

In assembling the switch, the conductors 32 and 34 are passed through the aperture in the plate 30 and their lower ends are thrust into the holes 22 and 24, as hereinbefore described. The fastening member is set on the base block and the shell 50 pushed down on the block and its lower edge is spun over the shoulder 16. The spring 60 is inserted in the shell and is surmounted by the washer 62 and plunger 70. An annular face plate 74 is then slipped over the plunger and pressed down against the flange 56. While in this position its outer margin is spun or curled around the edge of the flange 56, thus securing the face plate in its position on the upper end of the shell. The inner diameter of the face plate 74 is less than the inner diameter of shell 50 so that the inner margin projects over the shoulder 68 and thus prevents the plunger 70 from moving completely out of the shell 50. The shell 50, the base block 10 and the face plate 74 form a housing to enclose and protect the switch elements 32, 34 and 64.

The arms 44 and 46 of the spring fastening member 42 extend upward and diverge slightly from the surface of the shell 50 until they nearly reach the flange 56. The upper portions of these arms then bend inward as at 76 and 78 so that the upper extremities of the arms are beneath the rim 56 and near thereto. Thus when the switch is to be installed in a door jamb 80, the wire connections are first made by fishing out the terminals or plugs 38 through a preformed hole 82 in the door jamb. When the plugs have been thrust into the bores 18 and 20, the switch is

5 pushed into the hole 82 until the curled margin of the ring 74 abuts the door jamb and prevents further inward progress. As the switch is pushed into the hole, the diverging arms 44 and 46 are sprung toward each other as they ride on opposite portions of the edge of the hole. When the switch is pushed home, the inwardly sloping portion 76 of the arms bear against the edges of the hole and thus serve to hold the switch firmly in place without looseness. In order to prevent the switch from coming out of the hole, small locking tongues 84 may be struck up from the arms 44 and 46 to engage behind the wall of the door jamb 80. These tongues each present a surface toward the face plate 74 which is parallel to the face plate and therefore is parallel to the plane of the door jamb 80 when the switch is installed as indicated in Figure 4. These tongues thus serve to lock the switch against removal from the hole until the arms 44 and 46 are pressed toward each other by an external force sufficient to enable the tongues 84 to clear the margins of the door jamb around the hole.

I claim:

25 In an electric switch of the plunger type, a base block of insulation having two spaced bores therethrough and two rectangular holes between said bores extending down into said block from the top thereof and opening laterally into respective bores, said block having a tongue projecting up from the top thereof between said holes, two sides of said tongue being continuations of wall faces of said holes, a metal strip projecting up from each said hole, each said strip having a lower portion projecting slightly into the adjacent bore, an insulating disk upon the top face of the block, said disk having a central rectangular aperture having a width substantially equal to the combined thicknesses of said tongue and strips, a metal ring surrounding the upper portions of said strips, and means for moving said ring into and out of simultaneous contact with said strips.

40 HUGH W. BATCHELLER.
